Joseph Miller

United States Patent Office.

JOSEPH MILLER, OF ALLIANCE, OHIO.

Letters Patent No. 66,727, dated July 16, 1867.

IMPROVED WEATHER-STRIP.

The Schedule referred to in these Letters Patent and making part of the same.

TO ALL WHOM IT MAY CONCERN:

Be it known that I, JOSEPH MILLER, of Alliance, in the county of Stark, and State of Ohio, have invented certain new and useful improvements in Weather-Strips; and I do hereby declare that the following is a full and complete description of the same, reference being had to the accompanying drawings making a part of this specification, in which—

Figure 1 is a view of a door and portion of the casing or frame.

Figure 2 is a detached section to which reference will be made.

Like letters of reference refer to like parts in the views.

In the drawings A represents the door, which is represented as thrown open, and B the frame.

My improvement consists in the manner of securing the strip C to the door, which is connected to the lower part of the door, as represented, by cutting a groove in the door and allowing the edge of the strip to be placed in it in an inclined position, as shown in fig. 2. This is to allow the rain that comes against the door to run down, and the plate being inclined throws the water away from the foot of the door, so that none will pass under the edge into the room; also, by the edge of the strip being placed in the groove, no water can pass down between the door and strip, as it would do if the strip were just placed against it. This plate is held in position after being placed in this groove, as stated, by means of the brackets D, which are secured to the door, and the lower end forming a lip over the edge of the plate C, as seen at fig. 2, thus making a very permanent and secure manner of fastening the strip to the door in conjunction with the groove.

What I claim as my improvement, and desire to secure by Letters Patent, is—

Supporting the weather-strip C to the door in the groove by means of the brackets D, provided with the tip a, combined in the manner and for the purpose substantially as set forth.

JOSEPH MILLER.
